[57] CLAIM

The ornamental design for a cultural tie and collar, as shown.

DESCRIPTION

FIG. 1 is a front elevational view of a cultural tie and collar showing our new design;

FIG. 2 is a rear elevational view of a cultural tie and collar of FIG. 1;

FIG. 3 is a left side view of the cultural tie and collar of FIG. 1;

FIG. 4 is a right side view of the cultural tie and collar of FIG. 1;

FIG. 5 is a top plan view of the cultural tie and collar of FIG. 1; and,

FIG. 6 is a bottom plan view of the cultural tie and collar of FIG. 1.

The broken line showing of the shirt in FIGS. 1 and 2 is for illustrative purposes only and forms no part of the claimed design.
